(57) **CLAIM**

The ornamental design for a fan, as shown and described.

DESCRIPTION

FIG. 1 is a bottom plan view of a fan showing our new design;
FIG. 2 is a top plan view thereof;
FIG. 3 is a left side elevation view thereof;
FIG. 4 is a right side elevation view thereof;
FIG. 5 is a front elevation view thereof;
FIG. 6 is a rear elevation view thereof;
FIG. 7 is a perspective view thereof;
FIG. 8 is a reference bottom plan view
FIG. 9 is a reference top plan view thereof;
FIG. 10 is a reference left side elevation view thereof;
FIG. 11 is a reference right side elevation view thereof;
FIG. 12 is a reference front elevation view thereof;
FIG. 13 is a reference rear elevation view thereof; and,
FIG. 14 is a reference perspective view thereof.

The lead wires are shown broken away in FIGS. 3-6 to indicate indeterminate length, it being understood that the wires have uniform shape and appearance through their length.

The broken lines in FIGS. 8-14 represent unclaimed subject matter.

1 Claim, 14 Drawing Sheets
